UNITED STATES PATENT OFFICE.

BERNARD H. EDWARDS, OF SPRING HOPE, NORTH CAROLINA.

BED EXTENSION.

Application filed May 29, 1923. Serial No. 642,311.

To all whom it may concern:

Be it known that BERNARD H. EDWARDS, a citizen of the United States of America, residing at Spring Hope, in the county of 5 Nash and State of North Carolina, has invented new and useful Improvements in Bed Extensions, of which the following is a specification.

The object of the invention is to provide a simple and efficient construction 10 of extension for bedsteads of the conventional type whether of the iron or wooden construction which may readily be exposed for use or moved into a position beneath 15 and within the contour of the bedstead when not required and which will afford a substantial enlargement on the effective area 20 of the structure; and with this object in view the invention consists in a construction 25 and combination of parts of which a preferred embodiment is shown in the accompanying drawings, wherein:—

Figure 1 is a perspective view in outline 25 of a bedstead extension applied in the operative position to a conventional bedstead.

Figures 2 and 3 are cross sectional views showing the extension respectively in the folded and the extended positions.

Figure 4 is a detail view of a portion of 30 the frame 12.

Figure 5 is a detail perspective view of a portion of the frame 12 and one of the legs 29.

Figure 6 is a detail view of a part of the 35 frame 12, more clearly showing the socket 33 and staple 31.

The structure embodies essentially the 40 guide bars 10 adapted for arrangement transversely of and beneath the plane of the side rails 11 of a conventional bedstead frame, and an extension bedframe 12 which is mounted for movement upon said guide bars in a direction transversely of the main bed frame into positions respectively beneath and projecting laterally beyond the main frame.

In the construction illustrated these guide 45 bars in order to adapt them to be applied readily to bedsteads of different widths or 50 varying slightly in width, are of extensible construction having a receiving element 10^a telescopically fitted upon one end of the body portion of the bar and adapted to be secured in adjusted relation therewith by 55 suitable means such as a set screw 13. The

receiving element 10^a is provided with an integral hanger arm 19 supporting it from one of the side rails. Terminally each guide bar is provided with means for engaging one of the side rails of the main bed frame. At 60 that end of each guide bar which is engaged with the side rail beyond which the extension frame is to be projected in use, there is provided a bracket 14 extending upward outside of the side rail of the bed 65 frame and thence over and bearing upon the upper side thereof with the inner depending arm 15 provided with the terminal detent 16 which is engaged with a socket in an anchor block 18 which fits in the channel 70 of the side rail. At the other or rear end each guide bar is supported by the receiving element 10^a through its hanger arm 19 which is provided at its upper end with a detent 20 for engagement with a socket in 75 an anchor block 21 fitted in the channel of the side rail. Obviously by extending the guide bar and locking it through the agency of the set screw 13 it may be firmly secured 80 in place with relation to the main bedstead frame.

The extension bedframe is provided at its ends (which are in running relation with the guide rods 10) with guide rollers 23 to traverse the guide bars of said bed frame, and adjacent one longitudinal edge said extension bedframe is provided with hooks 24 or fastening means which may be engaged 90 with the brackets or front ends of the guide bars when the said extension frame is in the folded or collapsed position to hold the same against accidental extension.

At the center of its outer or front bar the extension frame is provided with a socket 25 for the reception of a leg 26 preferably provided with a caster roller 27 adapted to be secured in place by a set screw 28. This caster leg may be detached, if desired, but serves while in place as an additional guide and support for the outer or front edge of the extension bed frame in moving the latter from one position to another. As additional supporting means for the outer or front edge of the extension bedframe 95 when in use and in order that it may be enabled to uphold the weight imposed thereon, it is provided with foldable legs 29 which in the construction illustrated are slotted as at 30 to engage staples 31 depending from the extension bedframe, said 100 105 110

leg being provided with lugs 32 for engagement with a socket 33 also on the bed-frame. When the legs 29 are in folded positions the staples 31 enter the slots 30 to relieve strain on the means which connect the legs to the extension bed frame. When the legs 29 are extended the lugs 32 enter the sockets 33, the legs acting to afford substantial support for the extended bed frame.

10 Having described the invention, what is claimed as new and useful is:—

1. A side extension for a bedstead frame having transverse guide bars provided with terminal means for engagement respectively 15 with the angle iron side rails of the bedstead frame, an extension bed frame slidingly mounted upon said guide bars for movement into folded and extended positions with relation to the main bedframe and permanently supported at its inner edge by said 20 guide bars, means for supporting the outer edge of said extension bed frame when in its extended position, said guide bars being provided at certain of their ends with brackets lying beyond and having a return 25 part overhanging the side rail at one side of the bed frame and at the other ends with hanger arms, said brackets and hanger arms being provided with outwardly directed 30 studs, and anchor blocks adapted to be seated

in the angle of the bedstead side rails and having sockets for the reception of said studs.

2. The combination with a bedstead frame provided in its angle iron side rails with 35 anchor blocks provided with sockets, of hanger arms provided with outwardly directed studs engaging the sockets of certain of said blocks and having at their lower ends receiving elements, transverse guide 40 bars telescopically adjustable in said elements and having at their other ends brackets lying beyond, extending upwardly and return parts overhanging one of the side rails of the bedstead frame, the said overhanging parts of said brackets also having outwardly directed studs to engage the 45 sockets of the other of said blocks, an extension bed frame provided with rollers mounted on said guide bars and having movement in folded and extended positions with relation to the main bed frame, said rollers permanently supporting the inner portion of the extension bed frame, and means for supporting the outer portion of 50 said extension bed frame when in its extended position.

In testimony whereof he affixes his signature.

BERNARD H. EDWARDS.
